UNITED STATES PATENT OFFICE.

JOSEPH GOULBOURN, OF LEICESTER, ENGLAND, ASSIGNOR TO UNITED SHOE MACHINERY CORPORATION, OF PATERSON, NEW JERSEY, A CORPORATION OF NEW JERSEY.

EDGE-FINISHING MACHINE.

Application filed June 12, 1923, Serial No. 644,929, and in Great Britain July 8, 1922.

This invention relates to machines for use in the manufacture of boots and shoes and is illustrated herein as embodied in a machine employing heat in the operation of finishing the edge of a piece of upper leather.

In machines of this type the leather is commonly fed, flesh-side uppermost, over a table or support and beneath a hot tool which is mounted so as to be lifted by the leading end of the work and to bear yieldingly upon the work, the action of the tool being to sear and shrink the flesh side of the margin and thereby to cause the grain side to curl toward the flesh side so that the finished edge presents a surface which is all grain. In such machines there is sometimes a tendency for the searing and shrinking to be excessive at the leading end of the work where the tool rides up on it, and this undesirable effect is accentuated when two edges, which are finished by this treatment, meet. If, for example, the piece whose edges are to be finished has a sharp corner where two of its edges meet and the operation must be started and ended at this corner, the corner receives two heat treatments, one at the leading end of one edge (considered with respect to the direction of feed movement) and another at the trailing end of the other edge; and, in such case, the corner may lose much of the sharp character of its outline and become objectionably rounded.

According to one feature of the present invention, means operated by the work as it is fed are provided for determining the locality on the work at which the tool shall begin to operate. In the illustrative machine a roll which normally rests upon the work support is located in the path of feed movement of the work and is so connected with the tool that the tool is held in raised, inoperative position until the work is fed beneath and moves the roll whereupon the tool descends upon the work and continues in that operative position while the remaining portion of the edge of the work is fed past it. The roll is so located that the leading end of the work is fed to or past the tool before it reaches the roll, said roll being adjustable to vary its distance from the tool. With this construction the tool does not ride up on the work at all; and the tool may be rendered operative exactly at the leading end of the work or at a selected

distance from said end. In the case, referred to above, of a piece of work having two edges which meet in a sharp corner it is thus possible to treat the edge without going over the extreme corner more than once.

This and other features of the invention including certain details of construction and combinations of parts will be described as embodied in an illustrative machine and pointed out in the appended claims.

Referring now to the accompanying drawings,

Figure 1 is an end elevation of a portion of a machine in which the present invention is embodied, showing the parts in work-receiving position;

Fig. 2 is a side elevation, partly in section, of the parts shown in Fig. 1; and

Fig. 3 shows, on an enlarged scale, the positions of some of the parts shown in Fig. 1 when operating on a work piece.

The invention is shown as embodied in a machine of the type of that of British Patent No. 193,936; and before proceeding to describe what is new, the construction which is common to the patented machine and that of the present application will be briefly indicated. The machine has a work table or support 1 over which the leather or other sheet material 2 is fed (from right to left as viewed in Fig. 1) by feeding members 3 and 4, the work being held down upon the table by an idle presser wheel 5. These members serve to feed the work over the table with its edge in engagement with a plow or turning post 6, and its extreme upper margin in engagement with a hot searing or shrinking tool 7 which shrinks the upper side of the margin of the work and causes the other side to curl toward the shrunken side. After the edge of the work, thus shrunken and curled, has been fed past the tool 7 it is operated upon by a hammer, not shown, which increases the curl. The work operated upon is commonly a piece of leather which is fed flesh-side up; and the result of the operation is to produce a finished edge which presents a smooth grain surface. The tool 7 is mounted at the outer end of an overhanging arm 8 pivoted about an axis, not shown, located at one side of and extending parallel to the line of feed. This arm tends at all times to swing downwardly about the pivot so that the tool is

urged at all times toward the support. When no work is in the machine the tool is close to the support, being held in that position by a stop, not shown, which resists the weight of the pivoted arm. When a piece of work is fed along the support, the tool rides up on the leading end of the piece and rests upon the piece during the whole feed movement of the piece until the trailing end of the piece passes from beneath the tool. As thus far described, the illustrative machine is or may be substantially like the patented machine, and no further detailed description of the structure common to the two machines will be given.

In order normally to hold the tool 7 above the table a distance greater than the thickness of the work, and to permit the tool to descend upon the work at the desired time, a roll 9 is provided the axis of which is substantially perpendicular to the direction of feed movement of the work, the roll being so located that it will roll up on the work when the work is fed beneath it. The roll 9 is carried in a bracket 10 adjustably fixed to a member 11 by a screw 12 passing through a slot 13 in the member. The bracket 10 has formed on its upper face a tongue 14 which enters a groove 15 in the member 11. The screw and slot connection provides means for adjusting the bracket 10 and roll 9 toward or from the searing tool 7 laterally of the line of feed and parallel to the plane of the work. The member 11 is adjustably fixed to a bar 16 by a screw 17 passing through a slot 18 in the bar. The bar 16 is adjustably fixed at its upper end to a bracket 19 by a screw 20 passing through a slot 21 in the bar. The screws 17, 20 and slots 18, 21 permit of vertical adjustment of the bracket 10 and roll 9 to vary the height above the work of the searing tool 7 when the roll 9 is holding the arm 8 in raised position. The bracket 19 is fixed to a rod 22, which is mounted in the arm 8, by a screw 23 passing through a slot 24 in the bracket 19 so as to permit adjustment of the roll 9 toward or from the searing tool 7 along the line of feed.

The spindle 25 of the roll 9 is retained by a screw 26 and washer 27 in an upwardly curved guide slot or bearing 28 in the bracket 10 so that when the work is fed against the roll 9 as said roll rests upon the table, the roll spindle 25 will be pushed back (perpendicularly of its axis) along the gradually rising guide 28; and the bracket 10, arm 8 and tool 7 will descend until the tool bears upon the work. The guide 28 has formed in it a recess 29 which receives the spindle 25 when the arm 8 is raised and the roll 9 rests upon the table 1 so as to prevent the roll spindle from being pushed along the guide merely by the downward thrust upon it of the arm or from

being displaced by vibration of the machine so as to allow the arm to fall.

In the operation of the machine the tool 7 is thus held clear of the work until the leading edge of the latter encounters the roll 9 when it pushes the spindle 25 of the roll back out of the recess 29, and the tool 7 promptly drops upon the work. This movement of the tool to operative position may occur at the extreme forward edge of the work or somewhat rearward thereof, as indicated in Fig. 3, according to the setting of the roll bracket 10 along the line of feed. The device is automatically reset when the arm 8 is lifted at the end of an operation, since the roll spindle 25 then falls back to the lowest point of the curved guide, and the recess 29 and roll 9 reassume the mutual relationship in which the former more or less locks the latter against rearward movement under mere downward pressure of the arm. Consequently, when the arm 8 is again lowered, the roll 9 resting on the table 1 holds the tool 7 clear of the next work piece until the latter has advanced to the desired position.

Having thus described my invention, what I claim as new and desire to secure by Letters Patent of the United States is:

1. A machine of the class described having, in combination, a work support, a tool between which and the support the work is fed, said tool being urged at all times toward the support into position to engage the work, a member located in the path of feed movement of the work and adapted, when no work is being operated upon, to hold the tool in raised position, and connections between the member and tool such that movement of the member by the work permits the tool to fall.

2. A machine of the class described having, in combination, a work supporting member and an operating member, connections between said members such that one member tends at all times to approach the other, means for feeding the work between them, and a controller connected with one member and adapted first to contact with the other member to hold the two members spaced apart a distance greater than the thickness of the work and then to contact with and be moved by the work to permit the work to be operated upon.

3. A machine of the class described having, in combination, a work supporting member and an operating member, connections between said members such that one member tends at all times to approach the other, means for feeding the work between them, and a controller located behind the operating member considered in the direction of feed movement of the work, said controller being connected with one member and adapted first to contact with the

other member to hold the two members spaced apart a distance greater than the thickness of the work and then to contact with and be moved by the work to permit 5 the work to be operated upon.

4. A machine of the class described having, in combination, a work support, a tool movable toward and from the support, means for feeding the work over the support, a member connected with the tool and having a guideway included upwardly from the support in the direction of the feed movement and a roll located in the path of feed movement and having its axis mounted 10 in said guideway.

5. A machine of the class described having, in combination, a work support, a tool movable toward and from the support, means for feeding the work over the support, a member connected with the tool and having a guideway inclined upwardly from the support in the direction of the feed movement and provided at its lower end with an upwardly extending recess, and a 20 roll located in the path of feed movement and having its axis mounted in said guideway and normally located in said recess.

6. A machine of the class described having, in combination, a work support, a tool movable toward and from said support, means for feeding the work over the support, a member connected with the tool and having a guideway inclined upwardly from the support in the direction of feed movement, and a roll having its axis mounted in the guideway, the lowest portion of the roll extending normally below the level of the lowest portion of the tool in position to be engaged by the leading end of the work as 35 it is fed.

7. A machine of the class described having, in combination, a work support, a tool movable toward and from said support, means for feeding the work over the support, a member connected with the tool and having a guideway inclined upwardly from the support in the direction of feed movement, a roll having its axis mounted in the guideway, the lowest portion of the roll extending normally below the level of the lowest portion of the tool in position to be engaged by the leading end of the work as it is fed, and means whereby the member having the guideway may be adjusted toward and from the tool substantially in the line of feed.

8. A machine of the class described having, in combination, a work support, a tool movable toward and from said support, means for feeding the work over the support, a member connected with the tool and having a guideway inclined upwardly from the support in the direction of feed movement, a roll having its axis mounted in the guideway, the lowest portion of the roll ex-

tending normally below the level of the lowest portion of the tool in position to be engaged by the leading end of the work as it is fed, and means whereby the member having the guideway may be adjusted toward 70 and from the work support.

9. A machine of the class described having, in combination, a work support, a tool movable toward and from said support, means for feeding the work over the support, a member connected with the tool and having a guideway inclined upwardly from the support in the direction of feed movement, a roll having its axis mounted in the guideway, the lowest portion of the roll extending normally below the level of the lowest portion of the tool in position to be engaged by the leading end of the work as it is fed, and means whereby the member having the guideway may be adjusted in a direction substantially transverse to the line of feed.

10. A machine for finishing the edge of a piece of work having, in combination, a work support, a shrinking tool, means for feeding the work between the tool and the support in such manner that its margin is acted upon by the tool and means actuated by the work for causing the operation of the tool to begin at a point spaced from the leading end of the work.

11. A machine for finishing the edge of a piece of work having, in combination, a work support, a shrinking tool, means for feeding the work between the tool and the support in such manner that its margin is acted upon by the tool and a member located in the path of feed movement of the work for normally holding the tool in inoperative position, said member being movable by the work to cause the tool to be moved into operative position.

12. A machine for finishing the edge of a piece of work having, in combination, a work support, a shrinking tool, means for feeding the work between the tool and the support, a member located in the path of feed movement of the work for normally holding the tool in inoperative position, said member being movable by the work to cause the tool to be moved into operative position, and means whereby the member may be adjusted to vary the extent of the work which will be fed past the tool before the tool is moved into operative position.

13. A machine for finishing the edge of a piece of work having, in combination, a work supporting member and a searing member, connections between said members such that one member tends at all times to approach the other, means for feeding the work, and a controller connected with one member and adapted to contact first with the other member and then with the work 130

for predetermining the locality on the work at which the finishing member begins to operate.

14. A machine for finishing the edge of a piece of work having, in combination, a work supporting member and a searing member, connections between said members such that one member tends at all times to approach the other, means for feeding the work, a controller connected with one mem-

ber and adapted to contact first with the other member and then with the work for predetermining the locality on the work at which the finishing member begins to operate, and means whereby the controller may be adjusted to vary the predetermined locality.

In testimony whereof I have signed my name to this specification.

JOSEPH GOULDBOURN.

Certificate of Correction.

It is hereby certified that in Letters Patent No. 1,598,719, granted July 27, 1926, upon the application of Joseph Gouldbourn, of Leicester, England, for an improvement in "Edge-Finishing Machines," an error appears in the printed specification requiring correction as follows: Page 3, line 11, claim 4, for the word "included" read *inclined*; and that the said Letters Patent should be read with this correction therein that the same may conform to the record of the case in the Patent Office.

Signed and sealed this 14th day of December, A. D. 1926.

[SEAL.]

M. J. MOORE,
Acting Commissioner of Patents.
